UNITED STATES PATENT OFFICE.

JAMES ALEXANDER FLANAGAN, OF TORONTO, CANADA.

BOBBIN-WINDER FOR SEWING-MACHINES.

1,388,180.

Specification of Letters Patent. Patented Aug. 23, 1921.

Application filed April 30, 1919, Serial No. 293,663. Renewed June 15, 1921. Serial No. 477,720.

To all whom it may concern:

Be it known that I, JAMES ALEXANDER FLANAGAN, a subject of the King of Great Britain, residing at Toronto, in the county 5 of York and Dominion of Canada, have invented a certain new and useful Improvement in Bobbin-Winders for Sewing-Machines, of which the following is a full, clear, and exact description.

10 My present invention relates to a bobbin winding attachment for sewing machines, in which the bobbin spindle is mounted in a pivoted arm adapted to oscillate between an operative and an inoperative position, and 15 the friction wheel on said spindle is adapted to receive motion from the fly-wheel of the sewing machine to turn the spindle, and a pivoted latch is employed to yieldingly engage said arm and hold the friction wheel in 20 operative relation with the fly-wheel, the object of the invention being to utilize the thread wound on the bobbin as the winding proceeds to move said arm to a position where the friction wheel will be out of contact with the fly-wheel.

25 With this object in view I construct the bobbin winding attachment with a member which for convenience may be termed a cast-off arm and rigidly secure it to the wheel 30 guard so as to take a downwardly forwardly inclined direction. Near the upper end of the cast-off arm is pivoted the oscillating arm carrying the bobbin spindle, which in its operative position also takes a downwardly forwardly inclined direction. Journaled in the oscillating arm near its outer 35 end is the bobbin spindle provided with a friction wheel adapted to receive motion from the fly-wheel when the oscillating arm 40 is in its operative position, the oscillating arm being acted upon by a spring which tends to move it to and hold it in its inoperative position. Intermediate its ends, the oscillating arm is formed with a substantially vertical slot, and extending through 45 the slot is a latch which is preferably pivoted to the stationary cast-off arm. This latch is provided with a beveled shoulder engaging the edge of the slot, to yieldingly 50 maintain the oscillating arm in its operative position, and with a stop to arrest the movement of the oscillating arm when it has reached the limit of its inoperative position, the shoulder of the latch being yieldingly

55 maintained in engagement with the edge of the slot by a spring connected to the latch, and to the cast-off arm.

The cast-off arm has a stationary finger or member opposed to that part of the bobbin spindle on which the bobbin is mounted, 60 and against which presses the thread wound on the bobbin to gradually move the arm carrying the bobbin spindle from its operative position as the bobbin fills with thread, this movement of the arm displacing the 65 latch so that it will be free to move to the limit of its inoperative position.

In the accompanying drawings illustrating the invention, in the several figures of which like parts are similarly designated, 70 Figure 1 is an elevation of a portion of a sewing machine head and the hand-wheel or fly-wheel, with the bobbin winder in position. Fig. 2 is an elevation of the hand-wheel or fly-wheel also showing the winder 75 in position and showing the head of the machine and the needle shaft in cross-section. Fig. 3 is a perspective view of the friction wheel, its bracket and adjacent parts. Fig. 4 is a perspective view of the latch and its 80 stationary support.

The sewing machine arm 1, its hand-wheel or fly-wheel 2, and shaft 3 may be of any usual or approved construction. The arm 1 has the usual bearing 4 for the shaft 3 and 85 this bearing extends outwardly toward the hand-wheel or fly-wheel.

The bobbin winder, is preferably secured to a guard 5, having a flange 6 overhanging more or less the band groove of the hand wheel, and a segmental hub 7, the latter being adapted to fit the bearing 4 of the arm and to be secured thereon in any suitable manner, as by a screw 8, so as to remain stationary. 9 is an oscillating arm, pivotally 90 mounted upon a screw or stud 10 projecting from the guard 5, and having a bearing 11 for the bobbin spindle 12, one end of which is adapted to receive and engage the bobbin 13 and the other end of which carries a 100 friction wheel 14, which is adapted to turn in contact with a hub or boss or runway 15 of the hand-wheel or fly-wheel 2, so as to impart rotary motion to the spindle 12 and consequently to the bobbin. This arm 9 105 preferably takes a downwardly-forwardly inclined direction to bring the friction wheel into contact with the fly-wheel when it is in

its operative position. The arm 9 is provided with a substantially vertical slot 19 through which extends a latch 20 pivoted at 21 to a cast-off arm 22 which is rigidly 5 and immovably fastened to the guard 5.

This latch is engaged by a spring 23 connected at one end to the latch, and at the other end to the cast-off arm 22 and is formed between its ends, with a beveled 10 shoulder or offset 20^a to slidingly engage the edge of the slot 19 and so hold the arm 9 against the tension of the spring 16, that the friction wheel will be in engagement with the fly-wheel or hand-wheel, for the winding 15 of the bobbin as shown in Fig. 2, which may be termed the operative position of the winding mechanism, and with a stop 20^b at its free end to arrest the arm when it has reached the limit of movement in its inoperative 20 position hereinafter described.

Between the beveled shoulder or offset 20^a and the stop 20^b is a head 20^c, which under the influence of the spring 23 presses against the wall of the slot 19, when the parts are 25 in their inoperative position, and with the coaction of a spring 16, connected at one end to the arm 9 and at the other end to the cast-off arm 22, holds the arm 9 in its inoperative position, in which position the 30 friction wheel 14 will be out of operative engagement with the hand-wheel or fly-wheel. The lower end of the cast-off arm 22 has a laterally deflected member 24, parallel to the bobbin spindle, and this deflected member 24 35 has a stationary cast-off finger 25 curved substantially on an arc of a circle and extending into alinement with the thread-receiving portion of the bobbin. When the bobbin is filling, the thread comes into contact with the finger 25 and as the filling 40 proceeds, the thread exerts pressure against the finger and causes the arm 9 to move away from the finger. The edge of the slot 19 then moves along the beveled shoulder or offset 20^a 45 and presses the latch forward and ultimately enables the arm 9 to back off from the shoulder or offset 20^a, and carry the friction wheel out of engagement with the hand-wheel or fly-wheel and thus stop the winding. The arm 50 9 then moves upwardly along the head 20^c of the latch until its upward movement is arrested by the stop 20^b. When the arm 9 backs off the shoulder or off-set 20^a the spring 16 exerts its force on the arm 9 and 55 moves it outward from the fly-wheel until arrested by the stop 20^b. The arm and friction wheel are then in what may be termed the inoperative position of the winding mechanism. When the arm 9 reaches its inoperative 60 position the spring 16, assisted by the pressure of the head 20^c against the wall of the slot 19 securely holds the arm 9 against inadvertent return to its operative position. The wound bobbin may then be re-

moved and an empty bobbin put in its place 65 and the arm 9 snapped back into engagement with the shoulder or offset 20^a of its latch 20, and the winding may then proceed.

Obviously the winding of bobbins may proceed irrespective of the operation of the 70 sewing machine, and, as already stated, bobbin winding may be carried on as well when the sewing machine is stitching as when not stitching. In other words, there is no necessary interruption of the stitching or sewing 75 operation while the bobbin winding is proceeding.

Any suitable thread guide or distributor may be used. As herein shown a pin 26 is designed to receive the spool 27 from which the thread is to be unwound to fill the bobbin. This pin is mounted upon a projection 28 depending from the bearing 11, and this projection carries a support 29 on which is pivoted the thread guide 30, and this thread-guide has a slotted arm 31 which engages a pin 32 mounted eccentrically on a worm-wheel 33 journaled on the projection and engaging a worm 34 on the spindle 12. Thus it will be seen that by the rotation of the 90 spindle, the worm wheel is turned and the thread guide is caused to traverse the width of the bobbin, back and forth, to guide or lay the thread evenly on the bobbin.

Variations in the details of construction 95 and arrangement of parts are considered to be within the scope of the invention as herein claimed.

What I claim is:—

1. A bobbin winder for sewing machines, 100 comprising a pivoted arm adapted to oscillate between an operative and an inoperative position, a bobbin spindle mounted in said arm, a friction wheel on said spindle adapted to receive motion from the fly-wheel of the 105 sewing machine to turn the spindle, a pivoted latch to yieldingly engage said arm and hold the friction wheel in operative relation with the fly-wheel, and a stationary abutment opposed to the bobbin spindle and engaged by the thread wound on the bobbin as the winding proceeds to actuate the arm to displace the latch and then move said arm from its operative to its inoperative position. 110

2. A bobbin winder for sewing machines, 115 comprising a pivoted arm adapted to oscillate between an operative and an inoperative position, a bobbin spindle mounted in said arm, a friction wheel on said spindle adapted to receive motion from the fly-wheel of the 120 sewing machine to turn the spindle, a pivoted latch having a beveled shoulder to yieldingly engage said arm and hold the friction wheel in operative relation with the fly-wheel, and stationary means opposed to the 125 bobbin spindle and engaged by the thread wound on the bobbin as the winding proceeds to press the arm against said shoulder

to displace the latch and then move said arm from its operative to its inoperative position.

3. A bobbin winder for sewing machines, comprising a pivoted arm adapted to oscillate between an operative and an inoperative position, a bobbin spindle mounted in said arm, a friction wheel on said spindle adapted to receive motion from the fly-wheel of the sewing machine to turn the spindle, a pivoted latch having a beveled shoulder to yieldingly engage said arm and hold the friction wheel in operative relation with the fly-wheel, stationary means opposed to the bobbin spindle and engaged by the thread wound on the bobbin as the winding proceeds to press the arm against said shoulder to displace the latch and then move said arm from its operative to its inoperative position, and a stop for said latch to arrest the arm when it has moved to the limit of its inoperative position.

4. A bobbin winder for sewing machines, comprising a pivoted arm adapted to oscillate between an operative and an inoperative

position, a bobbin spindle mounted in said arm, a friction wheel on said spindle adapted to receive motion from the fly-wheel of the sewing machine to turn the spindle, a pivoted latch having a beveled shoulder to yieldingly engage said arm and hold the friction wheel in operative relation with the fly-wheel, stationary means opposed to the bobbin spindle and engaged by the thread wound on the bobbin as the winding proceeds to press the arm against said shoulder to displace the latch and then move the arm from its operative to its inoperative position, a spring to hold the arm in its inoperative position, and a spring acting upon the pivoted latch to maintain it in engagement with the arm.

In testimony whereof I have hereunto set my hand this twenty-eighth day of April, A. D. 1919.

JAMES ALEXANDER FLANAGAN.
